VARIABLE CAPACITY PUMP

John R. Betts, Kearney, Nebr.

Application December 18, 1939, Serial No. 309,817

20 Claims. (Cl. 103—41)

My invention relates to reciprocating pumps and the primary object of the invention is the provision of a piston of relatively large diameter to provide a pump of large capacity such as is required for irrigation or wherever a large volume of water is required.

It is also an object of the invention to employ wind power and to utilize most advantageously the available power whether the wind is light or strong.

Another object of the invention is to provide a pump which is designed to be operated by a windmill even though the wind is too light to actuate the pump at full capacity.

Another object is the provision of pistons of much larger diameter and capacity than the prior pistons.

Another object is the provision of a piston which may be expanded to form a water tight bearing with the well lining and which may be contracted when it is desired to withdraw the piston for repairs or other purposes.

Another object is the provision of a pump structure which may be lowered into or withdrawn as a unit from the well cavity.

Another object is the provision of a windmill operated pump which will not race and tear itself to pieces in strong winds.

Having in view these objects and others which will be pointed out in the following description, I will now refer to the drawings, in which—

Figure 1 is a vertical sectional view of a well with my pump installed therein.

Figure 2 is a vertical sectional view showing the lower portion of my pump.

Figure 3 is a vertical sectional view showing an intermediate portion of my pump.

Figure 4 is a horizontal sectional view in reduced scale showing the valve arrangement of the valve in the pistons as viewed from above.

Figure 5 is a vertical sectional broken view of the upper portion of my pump.

Figure 5A is a vertical sectional view of the valve arrangement for automatically lowering the pressures in the pump when the wind velocity is below normal.

Figure 6 is a view in perspective showing the device for lowering the water level during freezing weather.

Figure 7 is a vertical sectional view showing the lowermost part of a modified form of my pump.

Figure 8 is a vertical sectional view of the piston employed with the arrangement shown in Figure 7.

The bore of the well is formed in the usual manner but since it is my purpose to employ automobile tires and wheels for pistons, the bore is relatively large in diameter, the diameter being usually from ten inches to thirty-two inches. This bore is formed to a point beneath the water table at the bottom of which a cylindrical screen 10 is inserted. Above the screen 10 is a metallic annulus 11 which rests on the screen. This annulus has secured thereto and depending therefrom a conical screen 12, the parts being secured together as best shown in Figure 2. A metallic liner 13 is then placed in position resting on the annulus 11 and extending to and above the bore. The liner 13 is spaced from the walls of the bore and the annular space 14 is filled with concrete. The cylindrical liner 13 constitutes the working barrel of the pump, the inner surface of the liner 13 being smooth and unobstructed to form a smooth channel for the reciprocation of the pistons 15. In practice, the cylindrical screen 10 and at least six feet of the liner 13 are placed under water.

Referring now to Figure 2, it will be seen that the screen 12 is constructed with an annular shelf 16 on which rests the seat member 17 of the ball valve 18 which is preferably made from rubber or a rubber composition. It will be readily understood that this valve 18 will admit water from below but prevent passage of water down through the valve 17—18. The lower part of the well structure also includes a channel for a reserve supply of air under pressure for purposes to be subsequently explained.

Above the annular plate 11 is a lowermost valve, this being stationary and formed of an automobile tire and wheel. This tire rests in the tire rim 20 of the wheel 21. It is provided with check valves 22 which may be concentrically arranged as shown in Figure 4. These valves 22 are of common construction having a valve plate 23 which is spring pressed into closing position. Their structure is of the open type so that water which passes upwardly past the valve plate 23 will be discharged in the chamber above the valve. The valve 24 consists of the usual tire and inner tube which are well-known in the automobile art. It is inflated through connections 25 and 26 with the reserve reservoir 19 which to a certain extent controls the loss through leakage of air.

The lowermost valve 24 is stationary. The inner tube of that valve holds its pressure almost indefinitely since it is entirely under water at constant temperature at all times and since it

has no movement. Even should there be some variation in pressure of that valve, no interference in the operation of the pump will occur since the function of the valve 24 is merely to seal the working barrel at the periphery of the valve 24 to prevent the passage of water except through the valve. If, however, it becomes necessary or desirable to increase or to decrease the pressure of the valve 24, access to that valve may be had through the conduit 26 which is provided with a cap closure 26a and a valve stem 26b shown in Figure 5. It should be here noted that the casings of the pistons 15 and the valve 24 must be either smooth or they must have a tread which will prevent the passage of water past the peripheries of the casings.

The inner tubes of the reciprocating pistons 15 must be kept inflated and the inflation should be uniform for all of the pistons 15. The pressure on the tires shall at all times be more than the hydrostatic pressure of the water surrounding the tires. In any well, as soon as the maximum hydrostatic pressure has been ascertained, all that will be necessary is to set the tire pressure a few pounds above this hydrostatic pressure at which point it can be constantly maintained. For this purpose an air pipe 29 is connected to the valve stems of all of the pistons 15, terminating in a pressure tank 30 with a valve stem 31 at the upper end of the tubular piston rod 27. Above the pressure tank is an air pressure gauge 32, also secured to the piston rod 27. The pressure gauge 32 at all times gives the operator the necessary information as to the air pressure in the pistons 15 so as to enable him to increase or decrease the pressure through the valve 31.

Wind velocities vary greatly and between wide limits. Sometimes this wind velocity is such that it cannot perform the work of pumping water from wells of the large diameters which I employ even though it would function perfectly in wells of average diameter. At such times the wind velocity is too low to overcome the weight of water to be lifted by pistons of large diameter. In the upward stroke each piston 15 must carry the load of water but it is also compelled to overcome the suction beneath the moving pistons. At such times I employ the arrangement shown in Figures 5 and 5A. A check valve 33 is secured to the hollow piston rod 27 at a point above one of the pistons 15 to conduct water into the annular space surrounding the air conduit 26. The gate valve 34 admits water from the water line at a point above the normal water level and into and through a velocity valve 35 which connects the gate valve 34 to the check valve 33. The gate valve may be closed or opened, either wholly or partly, by means of a hand wheel 36 within convenient reach of the operator, the hand wheel being connected by means of a stem 37 to the gate valve 34. The velocity valve 35, as shown in Figure 5A, includes a ball 38 which is actuated by the flow of water through the velocity valve.

The water passing through the check valve 33 enters the hollow piston rod 27 and falls out through the lower open end of the piston rod and onto the valve system 24. It suddenly relieves the piston 15 of a small portion of its load of water, but what is still more important, it suddenly breaks the suction underneath the lowermost piston 15 and above the valve system 24. The mill wheel is thus enabled again to start the upward movement of the pistons on their upward stroke but this upward movement of the

75 pistons suddenly increases the suction underneath the piston. This increase in suction will be accompanied by a rapid rush of water to throw the ball 38 of the velocity valve upwardly to cut off all leakage flow through the check valve 33. This action is again sudden and it results in a sudden increase in the suction between the valve system 24 and the lowermost of the pistons 15. This increase in suction causes the 10 elevation of the water in the water line within the space surrounded by the cylindrical liner 13. This sudden increase in suction naturally brings up water through the suction line until, if the wind is extremely light, the mill may be finally brought to rest at which time the entire process will repeat itself. If the wind flow is extremely light, the ball check 38 may rise only partially. Thus the piston 15 may be operating on a partially broken vacuum which in turn will bring a correspondingly lighter flow through the check valve and suction line. The real point that I wish to bring out is that this automatic loading system will load the cylinder and the mill with water in proportion to the velocity of the wind. It can readily be seen that were it not for this unloading system, it would be necessary to normally equip the pump with a much smaller cylinder than the one above described. If there were no means of unloading, the load on the cylinder would be proportionate to the velocity of the wind, resulting in the balanced condition causing the mill to stand still and pump no water. By equipping the mill with an extraordinarily large cylinder such as I have described, the mill can still be kept loaded in very strong winds to a point whereby it will not race and tear itself to pieces, and at the same time gain a great deal more water capacity.

40 The piston rod 27 is in the form of a hollow cylinder extending from the top of the pump to the lowermost of the movable pistons 15. It is centered in the well, all of the pistons 15 being secured thereto to provide bearings in the liner 13 so that no shaft bearings are needed. The air conduit 26 is stationary within the reciprocating pump rod 27 with an annular cylindrical space therebetween. The air conduit 29, the reserve air pressure tank 30, and the check valve 33 are all secured externally to the piston rod 27 to reciprocate therewith. The cap 28 serves as an air-tight closure for the upper open end of the piston rod so that the air in the piston rod is not allowed to escape except through the bottom opening which is under water and through an opening especially provided for the purpose near the top of the pump rod. This opening leads into an air conduit 39 which is provided with a cap 40 for opening, or closing, or partly opening the air passage through the conduit 39.

45 The reciprocation of the hollow piston rod with its lower open end under water will develop fluctuations in air pressure in the space enclosed in the pump rod. On the downward stroke, the enclosed body of air tends to be compressed and this pressure is released while the pump rod is moving upwardly. These fluctuations may be read on the air pressure gauge 41 which is secured to the piston rod and spaced therefrom by a block 42, the pressure gauge being connected through an air conduit 43. By observing the fluctuations in air pressure as indicated by the gauge 41, the operator of the pump is enabled to properly adjust the cap 40 or gate valve 34 to control these fluctuations.

50 The air valve 40 can be so set that a slight

amount of air will enter during the upward stroke of the hollow piston rod 27. The purpose of entering this small volume of air is that it will be carried downward with the water entering through the gate valve 34 and this small volume of air will act as a cushion to prevent the pounding which normally occurs in the use of large pistons due to the lack of compressibility of the water. If there is no pounding or if there seems to be a little air in the water this valve can be left closed altogether. The main regulation will come from water through the gate valve 34 which can be adjusted manually to the desired point through the hand wheel 36. In light winds water flowing through the valve 34 will not only relieve the vacuum under the piston when the piston stops on its upward motion, but due to the utter lack of compressibility of the water, as soon as a very small volume enters through valve 34 not only will the vacuum under the piston 15 be relieved but the pressure on both sides of the piston 15 will equalize. When this happens the only weight supported on the pump rod of the mill will be the hollow piston rod 27 plus the weight of the piston 15 itself. It will be readily seen that this weight will be so light in proportion to the total load that would normally be lifted that the mill operating this equipment can easily overcome the inertia to get it started. When this is happening and the velocity of the piston 15 has reached any normal degree of speed, a vacuum will develop under the piston 15 which will in turn be transmitted through pipe 27 and pass through the check valve 33, through the automatic valve 35 and through the gate valve 34. This sudden increase of vacuum will immediately produce a corresponding rush of water which will pass into the gate valve 34, through the velocity valve 35, through the check valve 33 and through the piston 27. If the vacuum becomes high enough this rush will become great enough to throw the ball 38 into the aperture in the top of the cavity of the velocity valve 35 which will suddenly cut off all flow and give a high kick to the vacuum. This high vacuum will naturally cause valves 23 which are located in piston 24 to lift allowing water to enter and to be trapped above these valves in case the mill stops. If, however, the wind velocity is high enough to cause piston 15 to travel continuously then the ball check 38 will operate through a very rapid cycle and there will be very little loss of water. If it is desired to operate the ball 38 slowly then the orifice in the gate valve 34 may be closed to such a point that the operation of the ball 38 will be sluggish and make the operation slightly easier on the mill. It is not intended that the valve 35 shall be any special valve but may be any standard ball valve now on the market or any disk valve or inverted spool valve. This may be almost any vertical check just as long as it is used upside down and becomes particularly a matter of the balance between weight in the flapper of the ball check itself and the upward velocity of the water. It is only necessary to design this valve so that the water attains considerable velocity before this valve slams shut and it is the slamming of this valve shut that causes the rapid rise of vacuum through the hollow piston rod 27 and under the piston 15.

The gauge 41, which may be termed a rocking gauge, is a gauge that indicates both pressure and vacuum. This change of condition is happening in piston rod 27 and under piston 15. By 75

watching the operation of this gauge the operator will be able to adjust the gate valve 34 through the medium of the hand wheel 36 until the maximum throw between pressure and vacuum has been attained at which point he knows that the pump is lifting the maximum amount of water because the vacuum under 15 is attaining its highest point and this high vacuum naturally means the largest volume of water possible for each stroke. The gauge 32 is merely a pressure gauge to show the pressure in the moving pistons and as the operator by watching gauge 41 can read the maximum hydrostatic pressure he will readily be able to put air pressure in chamber 30 through the valve 31 so that the gauge 32 registers a few pounds above the maximum gauge pressure indicated on the gauge 41 during the pressure and of the stroke and as it is only necessary to have the pressure in the pistons 15 a few pounds above the hydrostatic pressure, the functions of the gauges can readily be seen.

Provision is also made for draining the water from above the frost line. A pipe 43 enters the well and passes through the liner 13. The valve 44 is controlled by means of a handle 45 to open and close the valve 44. The conduits 43 and 46 are partially imbedded in the concrete surrounding the liner 13. The water is thus allowed to drain to the frost line through a pipe 46 to the bottom of the well as indicated in Figure 2. In Figure 1 three water levels are indicated. The lowermost of these levels shown indicates the normal water table at the site of the installation. The intermediate level in the well casing indicates the position above which there is danger of freezing the water in the well chamber. The topmost level is the pumping level, the water being discharged at that level through a spout 47.

The pump is a pump of extraordinary capacity, but it is also extremely simple in construction and installation. The entire pump may be assembled above ground and then lowered through the cylindrical liner 13 until it seats on the annular shoulder as shown in Figure 2. After inflating the inner tubes of the pistons 15 and of the valve system 24 to the desired pressure and connecting the pump rod 27 to a windmill 50 or to other suitable source of power, the pump is ready for operation. All parts of the pump assembly are readily accessible by first deflating the inner tubes of the pistons 15 and of the valve system 24 and then hoisting the assembly as a unit out through the chamber formed by the liner 13.

The pump described lifts an enormous volume of water because of the large diameter of the pistons which are formed from automobile wheels and tires. These pneumatic tires are obtainable at relatively low cost and in numerous diameters. In many cases, however, it may be desirable that a pump of large capacity be installed with a piston whose diameter is less than that of the smallest tire available. In Figures 7 and 8 I show a pump of small diameter employing the principles above described. The well casing includes a liner 48 which is similar to the liner 13 in all respects except that in general it has a smaller diameter than the liner 13. The sand screen 49 is a conical extension of a hollow cylinder 50 projecting downwardly through the lower open end of the well casing 48. At the junction of the conical screen 49 and the cylindrical conduit 50 is a foot valve 51 with a guard 52 to

prevent displacement of the foot valve. At the upper end of the cylindrical conduit 50 the wall is turned down at its edge to rest on the annulus 53 having a sleeve 54 projecting downwardly therefrom. The ring 55 is trapezoidal in section and is welded at 56 to the well casing 48 at the bottom end thereof. The ring 55 and the sleeve 54 are separable because of the screw threaded relation. Between the annulus 53 and the ring 55 there is a gasket 57 of a rubber composition, the gasket being compressible by turning the annulus 53 on the ring 55. The gasket is preferably of the kind known in the trade as a Dresser gasket. The annulus 53 is provided with a bail 58 which may be grasped by any suitable tool either for turning the annulus or for hoisting the stationary parts of the pump out of the well through the casing 48.

The piston employed in the well 48 above the bail 58 includes a stem 59 in the form of a hollow cylinder which is open at its lower end. The rings 60 surround this stem. These rings are made of rubber or rubber composition or lignum vitae or other substance for which water is a natural lubricant. Spacers 61 of metal surround the stem 59 between each pair of rings 60. These spacers are of somewhat shorter diameter than the rings 60 which are of a size to fit snugly in the casing 48. The alternate rings 59 and spacers 61 are secured to the stem 59 by means of rings 62 which are screw threaded to the lower and upper ends of the stem 59. Above the piston assembly is a flanged plate 63 which is screw threaded in the upper extremity of the stem 59. This plate 63 has an aperture 64 providing a seat for the ball valve 65. Ribs 66 provide an open connection with the block 67 which carries the hollow tubular piston 68. A by-pass 69 connects the chamber of the piston 68 with the chamber of the stem 59.

In nearly all respects the modification shown in Figures 7 and 8 is similar to the construction previously described. The differences reside mainly in the absence of the air lines which supply the inner tubes of the pistons 15 and the valve system 24. Since no inflation is necessary, the air lines for inflating the inner tubes are also unnecessary. The construction shown in Figures 7 and 8 is designed for utilizing the valves 33, 34 and 35 since this valve arrangement may be secured to the piston rod 68 in the same manner as previously described in connection with the piston rod 21. The water which is drained through the check valve 33 would fall to the bottom of the chamber in the piston rod 68 and from thence it would pass through the by-pass 69 into the chamber of the stem 59.

An important feature of my invention is the specific form of piston which I employ. This includes a disc of metal or other suitable material and provided with one or more check valves which permit the flow of water in one direction but prevent its flow in the opposite direction. At the rim of the disc is a rim which is made in the form of the automobile tire rim and on this rim is seated an automobile tire consisting of a casing and an inner tube which may be inflated or deflated. Whereas the cost of an ordinary piston of the size required would be prohibitive, the cost of the piston as I construct it is comparatively low. Besides, the material of the casing is practically frictionless in the metallic cylinder which is lubricated with water.

The piston may be employed wherever water is to be moved through conduits. For example,

it may be desired to irrigate with water from a stream-fed pond. In cases like this the cylinder may be horizontal or inclined as well as vertical. One piston may respond to the stream flow to actuate another piston of smaller diameter to lift the water from the pond even though the stream flow may be inadequate for the purpose with the ordinary equipment. In other words, the equipment would function much as a hydraulic ram does by utilizing a portion of the stream flow to elevate a portion of the water.

Having thus described my invention in such full, clear, and exact terms that its construction and operation will be readily understood by others skilled in the art to which it pertains, what I claim as new and desire to secure by Letters Patent of the United States is:

1. In combination, a cylindrical well casing having an annular shelf at its lower portion, a cylindrical screen member passing through the central aperture of said annular shelf and having an out-turned annular member seated on said annular shelf, and a valve at the upper extremity of said screen member, said valve having an expandable and contractible rim bearing against said well casing, the arrangement being such that said screen member and said valve may be removed from the well casing by first contracting said rim.

2. A well casing and a pump, said casing being in the form of a concrete cylinder having a smooth metallic liner, an expandable and contractible piston within said casing for lifting the water in said well casing, a conduit passing through said concrete cylinder and through said liner at the frost line, said conduit passing downward within said concrete cylinder and imbedded in the concrete thereof and having a discharge opening immediately below the lower edge of said concrete cylinder.

3. A well casing and a pump, said pump including a check valve at the lower extremity thereof, said check valve having a hollow rim of inflatable material to provide a peripheral seal against said casing, means for inflating and deflating said hollow rim whereby said check valve may be inserted into and held immovably in said casing or withdrawn from said casing, a piston having a hollow rim of inflatable material, a piston rod secured to said piston, and an air conduit for inflating or deflating said hollow rim, said conduit being reciprocable with said piston rod and terminating near the top of said well casing within convenient reach of the operator.

4. A pump including a cylinder and a reciprocable piston therein, a piston rod projecting upwardly from said piston, said piston rod being in the form of a hollow cylinder and having a lower open end below the level of said piston, and a manually controlled check valve on said piston rod above said piston for conducting water from said cylinder into said piston rod to thus relieve said piston of a portion of its load and to simultaneously relieve the suction beneath said piston.

5. In combination, a well casing, a pump rod reciprocable within said casing, a piston secured to said pump rod, said piston comprising a flat thin disc having a flared tire rim at the periphery of said disc, a tire casing of a material for which water is a natural lubricant secured in said tire rim, an inner tube within said tire casing, and means for varying the pressure within said inner tube to vary the pressure exerted by said tire casing against said well casing.

6. In combination, a well casing, a pump rod reciprocable within said casing, a piston secured to said pump rod, said piston comprising a solid disc having a check valve extending therethrough, a tire rim at the periphery of said disc, a tire casing of a material for which water is a natural lubricant secured in said tire rim, an inner tube within said tire casing, and means for varying the pressure within said inner tube to vary the pressure exerted by said tire casing against said well casing.

7. In combination, a well casing, a flat thin disc within said casing and having a flared tire rim at the periphery of said disc, a circular row of check valves extending through said disc, said check valves being disposed concentrically with the axis of said disc and said well casing, a tire casing secured in said tire rim, an inner tube within said tire casing, and means for varying the pressure within said inner tube to vary the pressure exerted by said tire casing against said well casing.

8. A pump having a reciprocating piston adapted to be operated by a windmill, upwardly opening check valves in said piston, a by-pass of relatively small size around said piston and check valves, and check valve means in said by-pass normally operative to permit a flow of water through said by-pass from the upper side of said piston to the under side but effective upon said flow attaining a predetermined velocity to close off said flow.

9. A pump having a reciprocating piston adapted to be operated by a windmill, upwardly opening check valves in said piston, a by-pass of relatively small size around said piston and check valves, check valve means in said by-pass normally operative to permit a flow of water through said by-pass from the upper side of said piston to the under side but effective upon said flow attaining a predetermined velocity to close off said flow, and a manual shut-off valve in said by-pass for shutting off said by-pass when the wind velocity is great enough to operate said pump at full capacity.

10. In combination, a well casing, a disc within said casing and having a concavely curved rim at the periphery of said disc, a check valve extending through said disc, a tire casing of a material for which water is a natural lubricant secured in said tire rim, the radial depth of said tire being at least a third more than the depth of said rim so that the outer portion of said tire is free to flex transversely, an inner tube within said tire casing, and means for varying the pressure within said inner tube to vary the pressure exerted by said tire casing against said well casing.

11. In combination, a well casing, a pump rod reciprocable within said casing, a piston secured to said pump rod, said piston comprising a central portion and a concavely curved tire rim at the periphery of said central portion, a hollow tire casing of a material for which water is a natural lubricant secured in said tire rim, the radial depth of said tire being at least a third more than the depth of said rim so that the outer portion of said tire is free to flex transversely, and means within said casing for yieldably urging the same outwardly against said well casing.

12. In combination, a well casing, pump rod reciprocable within said casing, a piston secured to said pump rod, said piston comprising a central portion having a concavely curved tire rim at the periphery of said disc, a hollow tire casing

of a material for which water is a natural lubricant secured in said tire rim, the upper flange of said tire rim extending over less than half the radial depth of the tire and the lower flange of said rim over a greater portion of the tire but terminating a sufficient distance from the outer face of the casing to permit a limited amount of flexing of the casing downwardly, and means within said casing for yieldably urging the same outwardly against said well casing.

13. In combination, a well casing, a pump rod reciprocable within said casing, a piston secured to said pump rod, said piston comprising a central portion and a concavely curved tire rim at the periphery of said central portion, a tire casing of a material for which water is a natural lubricant secured in said tire rim, an inner tube within said tire casing, and means for varying the pressure within said inner tube to vary the pressure exerted by said tire casing against said well casing, the radial depth of said tire being at least a third more than the depth of said rim so that the outer portion of said tire is free to flex transversely.

14. In combination, a well casing, a pump rod reciprocable within said casing, a piston secured to said pump rod, said piston comprising a central portion and a concavely curved tire rim at the periphery of said disc, a tire casing of a material for which water is a natural lubricant secured in said tire rim, an inner tube within said tire casing, and a pressure chamber secured to the upper end of said pump rod and connected to said inner tube to maintain a predetermined pressure within said inner tube, the radial depth of said tire being at least a third more than the depth of said rim so that the outer portion of said tire is free to flex transversely.

15. A pump including a cylinder and a reciprocable piston therein, a piston rod projecting upwardly from said piston, said piston rod being in the form of a hollow cylinder and having a lower open end below the level of said piston, a connection through said hollow piston rod, above said piston for conducting the pumped fluid from said cylinder into said piston rod to thus relieve said piston of a portion of its load and to simultaneously relieve the suction beneath said piston, and a check valve in said connection normally effective to permit such flow of fluid through said connection but effective upon the velocity of the fluid reaching a predetermined value to shut off such flow.

16. A well casing and a pump, said casing being in the form of a cylinder, a piston within said casing for lifting the water in said well casing, and a conduit passing through said cylinder adjacent the frost line, said conduit passing downward within the wall of said cylinder and having a discharge opening below the frost line.

17. A well casing and a pump, said casing being in the form of a cylinder, a piston within said casing for lifting the water in said well casing, a conduit passing through said cylinder adjacent the frost line, said conduit passing downwardly and having a discharge opening below the frost line, and a valve in said conduit and having an operating member accessible from above the ground.

18. A well casing and a pump, said casing being in the form of a concrete cylinder having a smooth metallic liner, a piston within said casing for lifting the water in said well casing, a conduit passing through said concrete cylinder and through said liner adjacent the frost line,

said conduit passing downward within said concrete cylinder and imbedded in the concrete thereof and having a discharge opening below said piston, and a valve in said conduit and having an operating member accessible from above the ground.

19. In a pump, a piston having a piston rod, said piston rod being in the form of a hollow cylinder open below the piston at its lower extremity but closed at its upper extremity so as to result in an air cushion in said piston rod, the pressure of which air cushion increases on the down stroke and decreases on the upstroke of the piston, and a valve closure in the upper portion of said piston rod, said closure being effective to release air from the air cushion on the down stroke and admit air on the upstroke and said closure being adjustable as to air resistance to adjust the change in pressure in the air cushion during the pumping stroke.

20. A pump including a cylinder and a reciprocable piston therein, a piston rod projecting upwardly from said piston, said piston rod being in the form of a hollow cylinder and having a lower open end below the level of said piston, a check valve on said piston rod at a point above said piston for conducting water from said cylinder into said piston rod to thus relieve said piston of a portion of its load and to simultaneously relieve the suction beneath said piston and a further check valve at the outer extremity of said check valve effective in the event of the water flowing through said check valves attaining a predetermined velocity to check such flow of water for automatically controlling the flow of water into said piston rod in accordance with the speed of movement of said piston rod.

JOHN R. BETTS.
